UNITED STATES PATENT OFFICE.

JOSIAH S. TUTTLE AND JOHN M. WILSON, OF KANSAS CITY, KANSAS.

SPRING CULTIVATOR-TOOTH.

SPECIFICATION forming part of Letters Patent No. 642,510, dated January 30, 1900.

Application filed April 24, 1899. Serial No. 714,195. (No model.)

To all whom it may concern:

Be it known that we, JOSIAH S. TUTTLE and JOHN M. WILSON, citizens of the United States, residing at Kansas City, in the county of Wyandotte and State of Kansas, have invented 5 a new and useful Spring Cultivator-Tooth, of which the following is a specification.

Our invention relates to improvements in spring cultivator-teeth adapted to be used in 10 series or in gangs on cultivator implements; and the primary object of the invention is to provide means which will permit the tooth to move in an upward-and-rearward direction when it encounters a root, stone, or other barrier in the path thereof, whereby the liability 15 of injury to the tooth is minimized and the strain and draft on the tooth-beam are reduced to overcome bending thereof.

A further object of the invention is to arrange 20 the tooth-carrier elements in a manner to lock the tooth in its normal operative position against the strain and pressure of the soil through which the tooth is drawn by the implement; but these elements permit the desirable 25 upward-and-rearward movement of the tooth under the conditions recited.

The tooth-carrying devices of our invention sustain the draft of the tooth, so as to reduce the strain on the cultivator-beam, 30 thus prolonging the service of the implement and obviating injury to or bending of the beam. The tooth-supporting shank is pivoted to the beam at a point nearly in the vertical plane assumed by the shovel-point when 35 in its normal position, and thus insures the presentation of the shovel-point on the return of the parts to working position at such an angle as to effect its easy and proper entrance into the soil.

40 The invention consists in the novel construction, combination, and arrangement of parts, which will be hereinafter fully described and claimed.

To enable others to understand the invention, we have illustrated the preferred embodiment thereof in the accompanying drawings, forming a part of this specification, and in which—

Figure 1 is a perspective view of a yieldable 50 cultivator-tooth constructed in accordance with our invention. Fig. 2 is a side elevation showing by dotted lines the position

assumed by the tooth-carrying shank and the draft appliances on the elevation of the shovel-point. Fig. 3 is a cross-section through the 55 guide-clamp and the spring-stop, the plane of section being indicated by the dotted line 33 of Fig. 2.

The same numerals of reference denote like and corresponding parts in each of the several figures of the drawings.

In carrying our invention into practice we employ a cultivator or tooth beam 5, which in its general construction is similar to the beams used on ordinary cultivator implements, and the rear end of this beam is curved 65 downwardly and forwardly to provide the arm 6.

The tooth carrier or shank forming one of the elements of our improvement consists of 70 curved members or bars 7 8, which are spaced in parallel relation to each other to receive the arm 6 of the beam. The shovel or point 9 is fitted to a block 10, which is secured to the lower extremity of the shank or carrier 75 by means of the bolt 11; but the devices for fastening the shovel to the shank or carrier are ordinary in the art. The members of the carrier or shank are curved longitudinally to conform to the curvature of the arm 6 on the 80 rear end of the beam 5, and this arm is fitted loosely between the members of the shank, so as to guide it in its swinging adjustment and to afford a brace to the shank against lateral deflection when the shank assumes its normal 85 working position, (represented by full lines in Fig. 2.) The upper end of this curved carrier or shank is attached to the beam by a bolt 12, which lies nearly in the vertical plane assumed by the point of the shovel when the 90 latter and the carrier are in their normal working positions, and the employment of the curved carrier and the disposition of the pivot-bolt 12 therefor in the manner described provide for the proper upward-and-rearward 95 movement when the shovel encounters an obstruction or barrier in its path. This curvature of the carrier and disposition of the pivot 12 are, furthermore, advantageous, because the carrier and shovel are caused to travel in 100 an arc which will insure the proper presentation of the shovel-point to the slot in a manner to readily and freely enter the soil on the return movement of the shank and shovel to

their normal working positions, the arc of movement and the position assumed by the shovel and the carrier or shank therefor being indicated by dotted lines in Fig. 2.

- 5 13 14 designate a pair of arms which are provided with widened rear ends 15, applied laterally against opposite sides of the two-part shank or carrier and secured firmly thereto at a suitable distance below the pivot 12, 10 which unites the beam and carrier together. These arms extend forwardly from the curved shank or carrier, and they are pivoted to a pitman or drag-bar 16 by means of a transverse pivot 17.
- 15 On the cultivator-beam 5, at a point intermediate of its length, is mounted an angle or bell-crank lever 18, which lies transversely across the axial line of said beam and is fulcrumed directly thereto at a point intermediate 20 its length by a pivot-bolt 19, that passes through the angle-lever at or near the junction of its oppositely-inclined arms or members, said bolt also passing through the cultivator-beam 5. The forward end of the angle-lever 18 is connected to the corresponding end of the pitman or drag-bar 16 by means of a pivot-bolt 20, and thus the drag-bar, the lever, and the arms serve to pivotally connect the shank or carrier with the beam.
- 25 30 Secured firmly to the cultivator-beam at a point in rear of the fulcrum for the angle-lever 18 is a vertically-disposed guide-clip 21. This clip is in the form of an inverted loop fastened securely at 22 to the cultivator-beam 35 and extending a suitable distance above the latter, the opening in the loop being elongated vertically to provide for the proper play of a spring-actuated rod 23. The forward end of this rod is pivoted at 24 to the 40 rear end of the angle-lever 18, and said rod passes loosely through the vertically-elongated opening of the guide-clip 21. The rear extremity of the spring-rod is externally threaded at 25, and on said rod is loosely fitted a coiled retracting-spring 26. The forward end of this spring is fitted or seated against a washer 26^a, that bears against the rear edge of the fixed guide-clip 21, and on the threaded rear extremity of the rod 23 is 45 screwed a nut 27, that acts against a washer 28, which forms a seat for the rear end of the coiled spring 26. The rod 23 and the spring are adapted to be shifted through the elongated eye of the fixed clip 21 when the lever 50 is turned by the elevation of the tooth. The spring 26 normally holds the lever in a position nearly parallel to the axial line of the beam, and this lever draws the drag-bar or pitman in a forward direction, so that the 55 arms 13 14 will hold the carrier or shank in a proper working position. In this position of the pitman or drag-bar and the arms the pitman is raised so that the pivot 17, the lever-fulcrum 19, and the pivot 20 are nearly 60 in line with each other diagonally across the axial line of the beam. Owing to this relation of the pivots 17 20 and the lever-fulcrum

19 and the tension of the coiled spring 23 on the rear end of the lever the drag-bar, lever, and carrier-bars are locked firmly in their 70 normal positions, and the tension of this spring is such as to resist the tendency of the pivoted carrier or shank to move in an upward-and-rearward direction in the ordinary service of the shovel or point 9. The tension 75 of the spring and the locking of the carrier by the positions of the drag-bar and lever cause the shovel to be held in its working position against the pressure or resistance of the soil encountered by the shovel in the forward movement of the implement; but when the shovel meets with an obstruction or barrier—such as a root, a stone, or other immovable object—the shovel is forced rearwardly and upwardly to overcome the tension 80 of the spring, thereby throwing the lever 18 in a forward direction and permitting the pitman and carrier to move upwardly. In this forward movement of the lever the spring-rod and the spring thereon are free to travel 85 in an upward direction with relation to the fixed clip, and such forward movement of the lever increases the strength of the spring by compressing the latter, so that the shovel or point when it clears the obstruction will be 90 instantly returned to its lowered normal position.

As heretofore indicated, the curvature of the shank or carrier and the relation of the pivot to the normal position assumed by the 100 shovel insure the movement of the shovel in an arc which will facilitate its reentrance into the soil with ease and freedom.

One of the important features of our invention is the disposition or relation of the lever 105 and the drag-bar to the curved shank or carrier. This arrangement of the parts provides a brace between the carrier and the beam, which brace is adapted to take up most of the strain usually imposed upon the beam 110 and the upper end of the shank, so that the strain is transferred to and sustained by the arms 13 14, the drag-bar, and the lever, thereby relieving the beam of excessive strain and minimizing the liability of injury and break- 115 age to the beam.

Changes in the form, proportion, size, and the minor details of construction within the scope of the appended claims may be resorted to without departing from the spirit 120 or sacrificing any of the advantages of this invention.

What we claim is—

1. The combination with a cultivator-beam, and a shank or carrier pivoted thereto, of a drag-bar or pitman connected pivotally with said carrier at a point intermediate its length, and a spring-controlled lever connected pivotally to the front end of the drag-bar, the lever being so related to the drag-bar that 125 the pivots of the drag-bar will nearly aline with the fulcrum of the lever when the parts are in their normal positions, whereby the drag-bar and lever serve to lock the carrier 130

or shank in its normal position, substantially as described.

2. The combination with a cultivator-beam, of a curved shank or carrier pivoted at its upper end to said beam and equipped with a shovel at its lower end, arms fast with the carrier or shank at a point below the beam, a lever fulcrumed on said beam, a drag-bar or pitman having its ends jointed respectively to the arms and the lever, and a spring connected actively to the lever and normally holding the latter in a position where the drag-bar pivots are nearly alined with the fulcrum of the lever, substantially as described.

3. The combination with a cultivator-beam, and a pivoted shaft carrying a shovel, of a guide-clip fixed to said beam to extend upwardly therefrom and having a vertically-elongated eye or loop, an endwise-movable tension-rod fitted slidably in said clip and shiftable vertically in the elongated eye or loop thereof, a spring on said rod and seated against the clip and the rod to be shiftable

vertically with said rod and to be compressed on movement of the rod in one direction, a lever fulcrumed on the beam and connected to the rod, and a drag-bar connecting the lever and the shank, substantially as described.

4. The combination of a cultivator-beam having a curved rear arm, a two-part shank or carrier provided with a shovel at one end and arranged to embrace the curved arm of said beam, a pivot-bolt connecting the carrier to the beam, a drag-bar jointed to the carrier at a point between its pivot and the shovel, and a spring-controlled lever jointed to the drag-bar, substantially as described.

In testimony that we claim the foregoing as our own we have hereto affixed our signatures in the presence of two witnesses.

JOSIAH S. TUTTLE.
JOHN M. WILSON.
